DESIGN FOR A FLOOR SWITCH

Robert L. Stone, Guilford, and Frank E. Runge,
Branford, Conn., assignors to The Soundscriber
Corporation, New Haven, Conn., a corporation
of Connecticut

Application August 5, 1946, Serial No. 132,295

Term of patent 14 years

(Cl. D26—13)

To all whom it may concern:

Be it known that we, Robert L. Stone and Frank E. Runge, citizens of the United States of America, residing in the towns of Guilford and Branford, respectively, in the county of New Haven and State of Connecticut, have invented a new, original, and ornamental Design for Floor Switch, of which the following is a specification, reference being had to the accompanying drawing, forming part thereof.

Fig. 1 is a plan view of the floor switch showing our new design.

Fig. 2 is a side view of the same.

Fig. 3 is a front view of the same.

The characteristic features of our design reside in the portions shown in full lines.

We claim:

The ornamental design for a floor switch, as shown and described.

ROBERT L. STONE.
FRANK E. RUNGE.
